UNITED STATES PATENT OFFICE.

DAVID A. BEERY, OF SPRINGFIELD, OHIO.

MOLD FOR FIRE-KINDLERS.

SPECIFICATION forming part of Letters Patent No. 237,804, dated February 15, 1881.

Application filed January 8, 1881. (No model.)

To all whom it may concern:

Be it known that I, DAVID A. BEERY, of the city of Springfield, in the county of Clarke and State of Ohio, have invented a new and 5 useful Improvement in Molds for Fire-Kindlers, of which the following is a specification.

My invention relates to molds for that class of fire-kindlers which are made of a composition of sawdust, resin, &c., which mixture is 10 filled into the molds while in a heated state and subjected to pressure, and when sufficiently compressed and cooled is discharged from the molds and the operation repeated, as before.

15 The fire-kindler manufactured in my improved molds is made with a hole through it of the form of a star, it being easily understood by reference to the drawings.

The object of my invention is to render more 20 easy the operation of discharging the kindlers, and also to prevent breakage and loss of the same in freeing them from the molds.

Heretofore a single following-block has been used to press down the material in the several 25 compartments of the molding-frame, and if there is a greater or less amount in some than in others, the sections of the following-block, which enters the mold-boxes, being all rigidly attached together or comprised in a single 30 piece, the consequence is that it often sticks in the molds, and when raised therefrom by force, as it must necessarily be, portions of the kindlers are often broken off, attaching such broken parts to the face of one or more 35 of the sections of the follower. To obviate this I make an independent follower or separate block for each kindler-mold, and as these are loosely fitted they very readily adapt their faces to any inequality in the fillings, and after 40 pressure is complete can be easily raised without danger of detaching any portion of the material with which the mold is filled.

Figure 1 is a perspective view of the molding-frame and face-board to which it is hinged. 45 One of the following-blocks is also shown as it is placed in one of the mold-sections after the latter is filled with the composition for the kindler. Similar blocks are placed in each one of the sections of the molding-frame after 50 they are filled ready for the press. Fig. 2 is a top view of one of the sections shown broken

from the molding-frame. Fig. 3 is a bottom view of the star-shaped core-block, which extends from the bottom to the top of the molding-frame. It is cast with four flat arms or 55 bars extending laterally from its base, by which it is attached to the under side of the frame. Each core is separately attached to the under edge of the cross-rails of the molding-frame, so that in case of one of the series 60 becoming broken it can be easily detached and replaced by another. Fig. 4 is an elevation of the core and its attaching-bars. Fig. 5 is a corner section broken from the face-board. Fig. 6 is a perspective view of one of the following-blocks, showing its reverse or face side. 65

A is the molding-frame, within which are a series of square box-molds. Within these is seen a star-shaped block or core, a, which extends from the bottom of frame A to the top 70 of the same. A flat thin bar, c, extends at right angles from the base of a to each of the four sides of the mold-box b, lapping half-way under the edge of each rail of the section, and is secured thereto by screws. As these bars 75 are fastened upon the under edge of frame A, they necessarily project a distance equal to their thickness below it, and grooves are cut to receive them and the projecting points of the core-block (which is cast on a level with 80 their under sides) in the face-board B, as seen in Fig. 5 at e.

The following-block C has a star-shaped hole, d, cut through that part b' which enters the mold-section b, large enough to pass loosely 85 over the core a. It has a metal face-plate, c', screwed on to protect it, and a cap, f, to gage its depth.

The material is placed in the molds b around the cores a, and a following-block, C, placed 90 in each one before being put under the press. After it has been compressed and cooled sufficiently the molding-frame A is swung up from the face-board B, (to which it is hinged,) the followers C removed and the kindlers taken 95 out. The openings g within the mold, on each side of the bars c, allow the introduction of the fingers on the under side of the mold for that purpose.

I claim as my improvement—
1. In a mold for fire-kindlers, the combination, with frame A, having the elevated star.

shaped cores *a* attached thereto in its several mold-sections, of the face-board *B*, having grooves *e* for receiving the projecting bars *c* and the base of said cores, substantially as set forth.

2. In molds for fire-kindlers, the separately-attached cores, having a star-shaped body, *a*, and arms *c* extending from the base thereof at right angles to the same, substantially as shown, for the purpose set forth.

3. In molds for fire-kindlers having a series of mold-sections, as shown, the separate fol-

lowing-blocks *C*, as and for the purpose hereinbefore set forth.

4. In molds for fire-kindlers, the combination, with the frame *A*, hinged to the face-board *B*, and having the elevated star-shaped cores *a* and mold-sections *b*, of the following-blocks *C*, having face-plates *c'* and star-shaped holes *d*, as and for the purpose hereinbefore specified.

Attest: DAVID A. BEERY.
